US0D1052849S

(12) **United States Design Patent** (10) **Patent No.:** **US D1,052,849 S**
(45) **Date of Patent:** **** Dec. 3, 2024**

(54) **STRAP CONNECTOR**

(71) Applicant: **Hikers Co. LLC**, Kamuela, HI (US)

(72) Inventor: **Matthew A Morgan**, Sebastopol, CA (US)

(73) Assignee: **Hikers Co. LLC**, Kamuela, HI (US)

(**) Term: **15 Years**

(21) Appl. No.: **29/777,650**

(22) Filed: **Apr. 7, 2021**

(51) **LOC (14) Cl.** **02-07**

(52) **U.S. Cl.**

USPC **D2/640**

(58) **Field of Classification Search**

CLAIM

The ornamental design for a strap connector as shown and described.

DESCRIPTION

FIG. 1 is a perspective view of the strap connector, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dash-dash broken lines shown in FIGS. 1-3 illustrate portions of the strap connector that form no part of the

(Continued)

claimed design; The dash-dot broken lines shown in FIGS. 1-3 define the bounds of the claimed design and form no part thereof.

1 Claim, 5 Drawing Sheets
